United States Patent Office

Des. 212,570
Patented Oct. 29, 1968

212,570

X-RAY CABINET

Webster J. Daly, 1200 N. Maclay,
San Fernando, Calif. 40913

Filed Sept. 26, 1967, Ser. No. 8,747

Term of patent 14 years

(Cl. D83—1)

FIGURE 1 is a fragmentary perspective view of the X-ray cabinet and with open doors, embodying my design;

FIGURE 2 is a perspective view of the opposite side and top thereof, the back being plain.

I claim:

The ornamental design for an X-ray cabinet, substantially as shown and described.
